(No Model.)

L. HUSSEY.

APPARATUS FOR REHEATING EXHAUST STEAM AND HEATING AIR.

No. 276,588.

Patented May 1, 1883.

UNITED STATES PATENT OFFICE.

LEVI HUSSEY, OF NEW YORK, N. Y., ASSIGNOR OF ONE-HALF TO GEORGE W. DONALDSON, OF CRANFORD, NEW JERSEY.

APPARATUS FOR REHEATING EXHAUST-STEAM AND HEATING AIR.

SPECIFICATION forming part of Letters Patent No. 276,588, dated May 1, 1883.

Application filed August 19, 1882. (No model.)

To all whom it may concern:

Be it known that I, LEVI HUSSEY, of the city, county, and State of New York, have invented certain new and useful Improvements 55 in Apparatus for Reheating Exhaust-Steam and Heating Air, of which the following is a specification.

This invention has reference to an improved apparatus for reheating exhaust-steam and 10 utilizing the same for heating drying-rooms, feed-water apparatus, and other purposes, and also for using the same apparatus at night, when the steam-engine is not at work, for heating air and conducting the same to the different 15 parts of the building.

The invention consists of a system of pipes arranged in an extension-flue above the flue for conducting the products of combustion to the chimney, said system of pipes being connected with the valved exhaust-pipe of the steam-engine and by a valved conducting-pipe to radiators, feed-water heaters, or other apparatus. The system of heating-pipes is also provided with valved air inlet and outlet pipes, 25 which supply heated atmospheric air to the building when the steam-engine is stopped for the night.

In the accompanying drawings, Figure 1 represents a longitudinal section of my improved apparatus for reheating exhaust-steam and heating air. Fig. 2 is a vertical transverse section of the same; and Fig. 3, a detailed view, showing the connection of the pipes of the system.

Similar letters of reference indicate corresponding parts.

In the drawings, A represents a steam-boiler of any approved construction, and B the brick-work by which the same is supported. The 40 products of combustion are conducted from the furnace C along the bottom and sides of the boiler, then forward through the flues of the same, and then above the boiler, in the usual manner, to the chimney, as shown by the 45 arrows in Fig. 1. The draft-flue D above the boiler is extended in upward direction, so as to be large enough to form an extension-flue, D', within which a system of heating-pipes, E, is arranged. This system of pipes E is supported by the headers E' and by an intermediate transverse hanger or bracket plate, E'',

supported by the brick-work of the boiler-flue. The exhaust-pipe F of the steam-engine is connected with the header E' at one end of the system of pipes E, so that the exhaust-steam 55 from the same passes through the several tiers of inclined pipes to the header E' at the other end of the system, and thence by a connecting-pipe, F', to the radiators, feed-water heater, or other apparatus, by which means the reheated 60 steam may be utilized. The exhaust-pipe F is provided with a stop-cock, f, which, when opened, admits the exhaust-steam to pass through the system of heating-pipes E. In the passage through the pipes E the exhaust- 65 steam is heated up to a considerably higher temperature by utilizing the radiated heat of the products of combustion which pass through the flue D to the chimney, said reheated exhaust-steam being then used for heating up 70 drying-rooms and other spaces without any additional cost. The steam-conducting pipe F' is provided with a pressure-regulating valve, F², and with a pipe, F³, leading to the outside, 75 so as to regulate the proper pressure in the heating-pipes within the building and automatically permit the escape of steam of higher pressure.

As the system described is only capable for use as long as the steam-engine is kept running, which generally is only during the working-hours of the day, it is also necessary to provide means by which a certain amount of heat can be supplied to the different rooms of the building during the night, when the engine is not running. For this purpose a valved air-pipe, G, is arranged, which, like the regulating-pipe F³, passes outside of the furnace-walls B. This air-pipe is connected with the lower part of the header E' at one end of the 80 system of heating-pipes E, so that the air is drawn in, heated up in the pipes E in its passage through the same, and then conducted by the pipe G' and suitable registers to the different parts of the building. The valve f 85 of the exhaust-pipe has to be closed when the steam-engine is stopped for the night. Owing to the heat radiated by the banked fires of the boiler and the walls of the furnace and extension-flue, the system of heating-pipes is kept 90 at a sufficiently high degree of temperature to draw in atmospheric air and heat it in the pipes 95 100

E, furnishing thereby a continuous supply of heated air to the interior of the building. In this manner a building may be heated during the day by means of the reheated exhaust-
 5 steam from the engine to which a high temperature is imparted from the heat of the products of combustion on their way from the boiler-furnace to the chimney, and at night to a less degree by the hot air drawn through the
 10 system of heating-pipes, which, however, is sufficiently heated to prevent the rooms in the building from assuming too low a temperature. The air being thus kept warm through the night in the building, a higher temperature
 15 may be quickly established again as soon as the steam-engine is started again the next morning.

A building may thus be economically and effectively heated by the waste products of
 20 combustion from the boiler-furnace and the exhaust-steam from the engine, and thus a considerable saving as compared to direct steam or air heating apparatus obtained.

Having thus described my invention, I claim
 25 as new and desire to secure by Letters Patent—

1. The combination of a steam-boiler furnace, C, a draft-flue, D, having an extension-flue, D', a coil of heating-pipes, E, having headers E', the coil and headers being located
 30 in the extension-flue, a valved exhaust-pipe, F, leading from the engine to one header E', a steam-conducting pipe, F', connected to the

opposite header E', provided with a pressure relief-valve, F², and a pipe, F³, substantially as set forth.

2. The combination of a steam-boiler furnace, C, a draft-flue, D, having an extension-flue, D', above the same, a coil of heating-pipes, E, having headers E', arranged with the coil in the extension-flue, a valved air-induction pipe, G, connected to the lower part of one header E', and a valved air-eduction pipe, G', connected to the upper part of the opposite header E', substantially as set forth.

3. The combination of a draft-flue, D, of a steam-boiler furnace, an extension-flue, D', above the same, a system of heating-pipes, E, within the extension-flue, a valved exhaust-pipe, F, connected to one end of the heating-pipes, a steam-conducting pipe, F', having pipe F³, and regulating-valve F², connected to the opposite end of the system of heating-pipes, and valved air induction and eduction pipes G G', connected to opposite ends of the system of heating-pipes, substantially as specified.

In testimony that I claim the foregoing as my invention I have signed my name in presence of two subscribing witnesses.

LEVI HUSSEY.
